E. TOENNIESSEN
PRESSING OFF DEVICE FOR TUBES AND YARN BODIES
OF SPINNING AND DOUBLING FRAMES
Filed Jan. 8, 1927

UNITED STATES PATENT OFFICE.

ERNST TOENNIESSEN, OF TUBINGEN, GERMANY.

PRESSING-OFF DEVICE FOR TUBES AND YARN BODIES OF SPINNING AND DOUBLING FRAMES.

Application filed January 8, 1927, Serial No. 159,979, and in Germany January 11, 1926.

This invention relates to a pressing-off device for tubes and yarn bodies of spinning- and doubling frames, which device presses a whole row of tubes off their spindles. The object of the invention differentiates essentially from the known devices, serving for the same purpose, in that a guide rail is suitably arranged along the rows of spindles. The frame of the pressing-off device is fitted with a hand lever enabling the inclination of said frame on the guide rail, whereby the supporting point of the frame, viz, the pulleys, serve as points of oscillation or inclination. A second hand lever, fixed to the pressing-off comb, is further provided. The device is of simple construction and its manipulation is easy.

One form of construction is shown, by way of example, in the accompanying drawing.

A guide rail *s* is mounted on the spindle bearing plate, supporting the guide pulleys *r* of frame *R*. The frame *R*, which is of suitable rigid construction, can be rolled along the machine with the aid of the hand lever *H*. A comb *h'*, having its pivot point at *i*, is pivotally mounted on frame *R*. A hand lever *h* is fixed to the pivotable comb *h'* above the pivot point *i*.

The operation is as follows;

After the machine has been fully charged, the frame *R* is placed, with its pulleys *r* on the rail *s*, preferably taking lever *H* in the right hand, and lever *h* in the left hand. Now the frame *R* is brought into an inclined position away from the machine, by means of lever *H*, and the device is pushed in the correct position so that the teeth of the oscillable comb *h'* register with the intervals between the spindles, where-

upon, with the aid of the levers *h* and *H*, the comb is shifted underneath the tubes *h²*, or, if desired, also on the cones of the wound-up bobbins. In this position the frame *R* stands vertical. Lever *h* is now pressed downwardly which effects the oscillation of the comb *h'*, the teeth of which thus pressing the row of bobbins off their spindles. The improved device can now be rolled in front of the next row of spindles, where the hereinbefore-mentioned operation is repeated.

It will be clearly understood that the improved device does not impede the spinner during the spinning operation.

I claim—

1. In a pressing-off device for spinning- and doubling frames, a spindle bearing plate, a guide rail fixed to said spindle bearing plate in combination with a rigid frame with means for rolling the frame on the guide rail, means for oscillating the frame on the guide rail, a pressing-off comb pivotally mounted on said frame and means for oscillating said pressing-off comb on the frame, substantially as described and shown and for the purpose set forth.

2. In a pressing-off device for spinning- and doubling frames, a spindle bearing plate, a guide rail fixed to said spindle bearing plate in combination with a rigid frame with pulleys for rolling the frame on the guide rail, a lever for oscillating the frame on the guide rail, a pressing-off comb pivotally mounted on said frame and a lever for oscillating said pressing-off comb on the frame, substantially as described and shown and for the purpose set forth.

In testimony whereof I affix my signature.

ERNST TOENNIESSEN.
